UNITED STATES PATENT OFFICE.

GEORGE E. POGGEL, OF LOUISVILLE, KENTUCKY.

PROCESS AND APPARATUS FOR SEASONING AND RECTIFYING PAPER-STOCK.

1,325,044.

Specification of Letters Patent. Patented Dec. 16, 1919.

Application filed September 24, 1917. Serial No. 192,939.

To all whom it may concern:

Be it known that I, GEORGE E. POGGEL, a citizen of the United States, residing at Louisville, county of Jefferson, State of Kentucky, have invented certain new and useful Improvements in Processes and Apparatus for Seasoning and Rectifying Paper-Stock, of which the following is a specification.

10 This invention relates to a process and apparatus for seasoning and rectifying paper stock.

In the printing or lithographing of register work, it is the general practice to thoroughly season the paper stock prior to printing. The general practice has been to lay the stock out in small piles in racks and to suspend them in such manner that there may be a free circulation of air through the stock so that moisture may be eliminated and the paper dried. Considerable space has heretofore been required for this purpose and such space is not available for other uses due to the fact that a relatively high temperature is usually maintained. It has been proposed to use electric fans for blowing the air through the paper stock, to expedite seasoning, but this method is not always reliable when carried on in a large open space as it is impossible to regulate the humidity and sometimes more moisture is forced into the paper stock than is eliminated therefrom. Under present conditions it usually takes from one to four days to properly season or rectify paper stock which is fresh, or which has received one or more colors. It is just as necessary to rectify stock which has received one or more colors and become affected by the absorption of moisture, as it is to season fresh stock, because it is impossible to register the remaining colors required for completion of the work when the paper has stretched due to the absorption of moisture.

45 My process and apparatus reduce the time and space required to season paper stock and insure substantially perfect condition of the stock regardless of climatic conditions prevailing where the stock is rectified or seasoned.

In carrying out the process there is employed heating means, a fan for blowing air heated by said means into contact with the paper stock which is to be seasoned or rectified, and an inclosure for causing cir-

culation of the heated air, in a novel manner, so that it will pass and repass the stock.

The apparatus for carrying out the invention is self-contained and can be located at any desired point and moved from place to place. The paper is suspended from supports and the apparatus, which is portable, can be disposed in relation to paper in any desired locality, used to dry or season the paper, and then moved to another locality to treat other paper stock suspended by other supports. The invention is not limited, however, to the support of the paper independently of the seasoning or drying means.

70 In the accompanying drawings,

Figure 1 is a side elevation of the drying apparatus by itself.

Fig. 2 is a similar view showing the drying apparatus and paper support arranged for treatment of the paper, the cover or top being removed.

Fig. 3 is a side elevation taken at right angles to Fig. 1 but showing the top in position.

Fig. 4 is a front elevation, the door being removed, the top being in position and the apparatus in use;

Fig. 5 is a horizontal section on the line 4—4 of Fig. 4.

Fig. 6 a diagram of the circuits for the heaters and fan.

The invention is shown as embodying a paper support or rack which is separate from the drying apparatus, but I wish it to be understood that I do not limit the invention to such an arrangement.

The rack for supporting the paper sheets 11 comprises upright rods 8 supported in floor flanges 5 and connected by braces 25, 95 couplings 9 being provided for that purpose. The parallel sets of upright rods 8 are connected by paper supporting rods 24 from which the paper sheets 11 are suspended by hangers 10 of any suitable form, permitting the paper to be readily applied to or detached therefrom. In practice the paper stock 11 suspended from each rod 24 comprises from sixty to seventy-five sheets according to the thickness of the stock.

100 The portable means for effecting drying and seasoning of the paper 11 comprises a box-like oven or structure supported by casters 22 so that it may be moved from place to place and positioned relatively to

105

110

the sets of rods 8, 25, 24 used for suspending the paper stock 11. This permits treatment of paper in one locality and the moving of the apparatus to another paper suspending rack, without delay, for the treatment of paper in another locality of the room, thereby saving time and increasing production.

In an installation where only one paper suspending rack is used, however, only a few minutes will be required to take the paper out of the apparatus, after seasoning, and replace it with other stock which has to be treated.

15 The front and rear walls 18 of the oven are removable, being provided with handles 15 by which they may be taken off or placed in position and held by catches 14 and 16. These walls are of such a size 20 that the openings they cover are of ample dimensions to permit the paper stock 11 to be readily passed therethrough when suspending it by the hangers 10 or removing it therefrom. The sides 17 are stationary, 25 the lower portions thereof being provided with inner parallel walls 23 to provide vertical channels. Movable panels 12 hinged at their lower ends 12^a to the upper edges of walls 23 in any suitable manner, define, 30 between themselves and the walls 17, the remaining portions of a double-walled structure through which the heated air currents may dive and pass into the spaces between the walls 23 and 17, as shown by the 35 long arrows in Fig. 4. The upper, the free, ends of the panels 12 are designed to rest against the edges of the suspended paper sheets 11. When the stock 11 is placed in position or removed, the panels 12 are moved 40 aside by hand, but during operation, or carrying out of the drying or curing process, these panels remain as shown in Fig. 4.

The top 13 is removable to permit the drying apparatus to be rolled under the rods 45 24 and between the upright rods 8.

Supported by the bottom of the apparatus, in a stand 7, is a stem 6 which is adjustable up and down and may be secured, where adjusted, by a set screw 6^a. Carried by the stem 6 is a fan 2 whose blades are arranged to revolve in a horizontal plane. Secured to, and supported by, the fan casing in any suitable manner are radiating tubular arms 3 which carry electrical 55 resistance heaters 1 which are located above the fan 2. The different electrical heaters 1 are controlled by switches 19 and 20. As shown in Fig. 6, the fan 2 is controlled by the main knife switch 21 and 60 runs whenever said switch is closed, regardless of whether the heaters 1 are on or not. The heaters 1 are arranged in pairs in respective circuits controlled by the switches 19 and 20. Either switch, 19, 20, or both, 65 may be open or closed, affording the volume

of heat and temperature desired. According to whether more or less of the heaters 1 are in use, variation in the temperature may be had to meet requirements of the paper stock being treated. Raising and 70 lowering the fan 2 and heaters 1 and setting them by the set screw 6^a where desired, enables them to be brought close to the lower ends of the sheets 11 so that the current of air forced by the fan causes the paper to 75 flare out and separate which allows for quick curing of the paper.

The hollow stem 6 and tubular arms 3 contain the wires leading from the switches 19, 20, 21 to the fan and heaters, so that 80 there are no protruding parts to interfere with the operation of the fan or the free passage of the air.

Operation: The apparatus having been moved to proper position between the uprights 8, the front wall 18 is removed and the panels or inner walls 12 held back. The stock is then suspended by the hangers 10 from the rods 24. The panels 12 are then allowed to rest against the stock as 90 shown in Fig. 4. The top 13, which was previously off, is now placed in position and the front wall 18 closed and held by the catches 14 and 16. The parts are then in the condition shown in Fig. 4, the paper 95 stock 11 being completely inclosed within the shell or casing of the apparatus. The fan 2 and heating means 1 having been raised to the proper point, according to the size of the paper 11 being cured, the desired temperature is obtained by turning on one or both of the switches 19, 20. Switch 21 being closed, the fan is set in revolution and blows the air upwardly between the sheets 11, as shown by the vertical arrows. 100 The heated air striking the top 13 is deflected and dives down between the panels 12 and the sides 18, thence passing between the inner walls 23 and the sides and reacting against the bottom of the shell only to be again blown upwardly by the fan and heated by the electrical heaters 1. In practice a temperature of 135 degrees is attained in a few minutes, and if this temperature is maintained for a period of, say, 115 twenty minutes, all of the moisture will be baked out of the stock 11. The switches 18 and 20 are then opened to cut off the heat and the front and rear walls removed while the fan 2 is allowed to continue to 120 run for a few minutes longer, during which period the temperature of the stock is reduced to the temperature for printing.

Having thus described my invention, what I claim as new and desire to secure by Letters Patent is:—

1. The process of seasoning and rectifying paper stock consisting in blowing currents of heated air upwardly between the sheets while the latter are suspended within an 130

closure and conducting the heated air, after passage between the sheets, exteriorly thereof back to the point where it is blown between the sheets, thereby maintaining a cycle 5 of travel of the air so that it is made to pass and repass the sheets.

2. The process of seasoning and rectifying paper stock consisting in forcibly passing and repassing currents of heated air upwardly between the sheets while the latter are in suspended condition and in conducting the heated air exteriorly of the paper back to the initial point of entry between the sheets, thereby maintaining cycles of 15 travel of the heated air during such passing and repassing thereof.

3. An apparatus for seasoning and rectifying paper stock comprising a shell or inclosing structure for the paper stock, means 20 for suspending the paper stock therein, heat producing means, and a fan for blowing air heated by said heating means upwardly into contact with the paper stock suspended within the inclosing structure.

25 4. An apparatus for seasoning and rectifying paper stock comprising a shell or inclosing structure for the paper stock, means for suspending the paper stock therein, heat producing means, and a fan for blowing air 30 heated by said heating means upwardly into contact with the paper stock, said shell or inclosure being provided with diving flues for returning the air to the fan, whereby the currents of air forced upwardly by the fan 35 travel in cycles and are repeatedly repassed in contact with the sheets of the stock.

5. In an apparatus for seasoning and rectifying paper stock, the combination with a shell or inclosure, of means for suspending paper stock therein, hinged walls or 40 panels adapted to rest against the paper stock and which define, in connection with walls of the shell, diving flues, a fan, and heating means arranged so that air blown from said fan passes over said heating 45 means, thereby directing heated currents of air to the sheets of the paper stock and inducing air currents which, after traversing

the sheets of the stock, dive down the flues aforesaid for re-blowing, re-heating and re- 50 passage of the paper stock.

6. In an apparatus for seasoning and rectifying paper stock, the combination with a rack for suspending the stock, of a shell or inclosure having a removable top, hinged 55 panels carried by the shell or inclosure which are adapted to rest against the paper stock when the latter is in position within the shell or inclosure, heating means and a fan carried by the shell or inclosure and adjustable in relation to the paper stock so that they may be set according to the size of the stock being treated, said fan being adapted to blow air over said heating means and into contact with the paper stock and to create 60 currents of heated air which travel in cycles and dive down the flues defined between the panels and the walls of the shell or inclosure.

7. The process of seasoning and rectifying paper stock consisting in forcibly blowing a current of heated air through the paper stock when confined in an inclosure, and afterward exposing the paper stock to the outer air and blowing cooler air there- 70 again.

8. In an apparatus for seasoning and rectifying paper stock, the combination with means for suspending paper stock, of a bodily movable shell or housing adapted to be shifted into inclosing relation to the paper 80 stock, or, away therefrom, and means for drying the paper when the shell is arranged in inclosing relation to the latter.

9. In an apparatus for seasoning and rectifying paper stock, the combination with means for suspending paper stock, of a bodily movable shell or housing adapted to be shifted into inclosing relation to the paper stock, or, away therefrom, and a fan and heater carried by and movable with said 90 shell, adapted for supplying heated air to the paper when the shell is in inclosing relation to the latter.

In testimony whereof, I hereunto affix my signature.

GEORGE E. POGGEL.
